UNITED STATES PATENT OFFICE

HENRI C. J. H. GELISSEN, OF DEVENTER, NETHERLANDS, AND FRANCISCUS VISSER'T HOOFT, OF BUFFALO, NEW YORK, ASSIGNEES, BY DIRECT AND MESNE ASSIGNMENTS, TO NOVADEL-AGENE CORPORATION, OF NEWARK, NEW JERSEY, A CORPORATION OF DELAWARE

TREATMENT OF EDIBLE MILLING PRODUCTS

No Drawing.

Application filed April 5, 1928. Serial No. 267,794.

The present invention relates to a process of treating flour, meal, or other edible milling products, and a composition for use in such treatment, and the product of such treatment. The invention constitutes an improvement upon certain prior patents including Sutherland No. 1,539,701, in which organic peroxid compounds are employed for the treatment of flour for improving its keeping qualities and baking qualities and for bleaching the same, and constitutes an improvement by virtue of which the activity of the peroxidized compounds is increased and quickened.

We have now demonstrated that if a substance is used with the peroxidized compound, which substance is somewhat volatile, and which carries the peroxidized compound with it when it vaporizes, the improvement of the flour and the bleaching thereof is considerably hastened, and on account of the fact that the benzoyl peroxid or other peroxidized compound is volatilized, during the operation; it is not necessary that the benzoyl peroxid should be ground to the exceeding small size of particles as indicated for example in the patents to Kroeber Nos. 1,555,805 and 1,565,375, and the expense of such fine grinding operation is accordingly avoided.

In accordance with the present invention the peroxidized compound can be used in a state of ordinary fine powder.

Some of the organic substances which are volatile occur both in the crystallized condition and the amorphous condition. The amorphous condition generally is more readily volatile than the crystallized substance, and accordingly we prefer to use the volatile substance in an amorphous condition, rather than in the crystalline condition. The process can be carried out frequently at room temperature, and with some of the substances which may be employed, temperatures somewhat above ordinary room temperature may be found preferable.

For the purpose of more completely explaining the nature of the invention, the following example is given, but the invention is not restricted to this specific example, since not only the substances here referred to can

be employed, but other substances having a like effect.

0.003% of benzoyl peroxid and the same percentage of benzoic acid, in an amorphous state were mixed with freshly milled flour from mixed wheat. The mixing was performed at room temperature and the benzoyl peroxid and benzoic acid were both in the form of powders although not reduced to the very fine state referred to in the patents to Kroeber. The mixture was allowed to stand at room temperature for six hours, and it was found that the bleaching of the flour had been effected to a very great degree. In a parallel experiment the same percentage of benzoyl peroxid, but without the benzoic acid, was added to the same quantity of the same kind of flour and allowed to stand six hours. In this case substantially no bleaching of the flour had taken place.

The results of this pair of experiments showed that the use of the benzoic acid, which is a somewhat volatile material, very greatly accelerated the bleaching of the flour, and the improved result is due, in our opinion, to the fact that the benzoic acid is somewhat volatile, and in volatilizing it carries with it the vapors of benzoyl peroxid, which itself is far less volatile than benzoic acid, but when mixed with benzoic acid, the volatility thereof is substantially increased.

While the very fine grinding of the Kroeber patents has been found useful in connection with the use of peroxidized compounds, we find that when a somewhat volatile substance of the class herein mentioned is employed, the peroxidized substance can be employed in the form of even a relatively coarse powder, containing particles up to say one hundred microns in size.

While we have above referred to the use of solid peroxidized compounds (including benzoyl peroxid), liquid peroxidized compounds (including liquid peroxids) can be used. Likewise, as the vaporizable substance, solids or liquids can be employed.

We claim:—

1. A process of treating edible milling products with an organic peroxidized compound which comprises treating said prod-

5 ucts with a mixture of an organic peroxidized compound in an amorphous state and a substance which increases the rate of volatilization of said peroxidized compound, whereby the action of such peroxidized compound, upon said milling product is accelerated.

10 2. A process of treating edible milling products with an organic peroxidized compound which comprises treating said products with a mixture of an organic peroxidized compound in an amorphous state and a substance which is slowly vaporizable at room temperature, and which substance when it volatilizes causes said peroxidized compound to vaporize.

15 3. In the treatment of flour, meal and other edible milling products, the herein described process which comprises adding a minute proportion of an organic peroxidized compound and of an organic substance which at room temperature is somewhat volatile, and which in volatilizing in the presence of such peroxidized compound causes the latter to also volatilize, and allowing volatilization of such added substances, whereby rapid bleaching is effected even though the said peroxidized compound is not ground to an impalpable powder.

20 4. A process which comprises mixing an edible milling product with small amounts of an organic peroxidized compound and amorphous benzoic acid.

25 5. A process which comprises mixing an edible milling product with small amounts of benzoyl peroxid and amorphous benzoic acid.

30 6. A process of treating flour and like milling products which comprises the step of mixing the same with benzoyl peroxid and an amorphous substance which is capable of inducing volatilization of the latter.

35 7. In the treatment of an edible milling product by action of a peroxidized organic body, the herein described step of accelerating action of the said body which comprises inducing vaporization thereof, in the presence of the said edible product under treatment.

40 8. In the treatment of an edible milling product by action of a peroxidized organic body, the herein described step of accelerating action of the said body which comprises inducing vaporization thereof in the presence of the said edible product under treatment, by vaporization of another organic substance which upon vaporization carries said peroxidized body into the vapor state.

45 9. A new agent for treating edible milling products as described, the same comprising an organic peroxidized compound and an amorphous substance which is volatile and which, upon vaporization in the presence of said peroxidized compound, induces volatilization of said latter.

50 10. A new agent for treating edible milling products as described, the same comprising

5 ing an organic peroxidized compound and amorphous benzoic acid, the latter being capable of inducing volatilization of said peroxidized compound.

11. A new agent for the treatment of 70 edible milling products which comprises benzoyl peroxid and amorphous benzoic acid.

12. A product comprising an edible milling product mixed with a composition as set forth in claim 9.

75 13. A product comprising an edible milling product mixed with a composition as set forth in claim 10.

14. A product comprising an edible milling product mixed with a composition as set forth in claim 11.

80 In testimony whereof we affix our signatures.
